COUCH BED

Joseph Martin, Laurelton, N. Y., assignor to
 United States Cabinet Bed Co., Brooklyn, N. Y.,
 a corporation of New York

Application March 1, 1941, Serial No. 381,265

20 Claims. (Cl. 5—13)

This invention relates to couch beds in general and more particularly to combination couch beds in which the couch bed in couch formation presents a love seat or two seat item and in bed formation embraces two or more sections.

Among the objects of the present invention, it is aimed to provide a couch bed having at least two movable bed sections, including frames which in open bed forming position are disposed in substantial alignment with one another and in closed couch position are spaced from one another to form a mattress receiving chamber.

It is still another object of the present invention to provide an improved three section couch bed in which the back forming section aligns with the two other sections including a seat section and a depressible section to form a bed in one position and which in couch formation is erect with the depressible section depressed and the seat forming section disposed above or spaced from the depressible section.

It is still another object of the present invention to provide an improved couch bed in which in couch formation a love seat or two seat couch is produced and in bed formation a three section bed is produced.

These and other features, capabilities and advantages of the invention will appear from one specific embodiment thereof illustrated in the accompanying drawings in which:

Fig. 1 is a plan of the couch bed in bed formation;

Fig. 2 is a side elevation of the couch bed in bed formation with one arm portion removed;

Fig. 3 is a side elevation of the couch bed in an intermediate position while being converted from bed formation into couch formation with one arm portion removed;

Fig. 4 is a side elevation of the couch bed in couch formation with one arm portion removed;

Fig. 5 is a section on the line 5—5 of Fig. 4;

Fig. 6 is a section on the line 6—6 of Fig. 4; and

Fig. 7 is a perspective of the couch bed in couch formation.

In the embodiment shown there is provided a main frame or section 1, to which are operatively connected the frames or sections 2, 3 and 4. The frame 2 constitutes an interchangeable back and bed section, the frame 3 an interchangeable bed section and lower platform for a mattress receiving chamber, and the frame 4 an interchangeable bed section and seat section.

The main frame 1 includes the angle iron side bars 5 and 6, the rear frame member 7 extend-

ing upwardly from the rear ends of the side bars 5 and 6. The side bars 5 and 6, in turn, are secured to the lower ends of the inner sides of the upholstered arm portions 8 and 9.

The section 2 consists essentially of a rectangular frame 10 having an upholstered back portion 11 mounted thereon. To the ends of the frame 10 there are secured the flat metal bars 12, one end of each of which extends adjacent to the longitudinal side of the frame 2 but preferably slightly removed from the rear face thereof, and the other end of which bars 12 extend adjacent to the rear face but removed from the inner longitudinal side of the frame 2.

To the inner ends of the bars 12 there are pivotally connected the links 13 and 14. The other ends of the links 13 and 14 are connected to the inner faces of the side bars 5 and 6, preferably a short distance removed from the rear ends of the side bars 5 and 6. To the outer faces of the bars 12, removed from the ends thereof adjacent the rear face of the frame 2, there are pivotally connected one of the ends of the bent links 15 and 16, the other ends of which links 15 and 16 are pivotally connected to the inner faces of the side bars 5 and 6, respectively. At the upper end of the frame portion 7 there is secured the angle iron 17 with one of its webs extending horizontally and at the upper end of the angle iron 17.

In bed formation, the links 13, 14, 15 and 16 extend forwardly and the rear edges of the frame 10 rest on the angle iron 17, all as shown in Fig. 2. To counteract the weight of the back 2 when raising the same and to dampen the sound when moving from one position to another the springs 115 and 116 are provided secured at one of their ends to the upper ends of the frame portion 7 and at their other ends to the links 15 and 16 adjacent their pivotal connection with the bars 12, 12.

The frames 3 and 4 may cooperate with one another to form a two section bed in one position and a seat with an intervening mattress compartment in another position, or else cooperate with the section 2 to form two parts of a three section bed, see Fig. 2, in one position and, in turn, an intervening mattress compartment with a seat to cooperate with the section 2 as the back forming portion of a couch, love seat or the like.

The frames 3 and 4 are essentially rectangular metal frame members 18 and 19 provided with the wire fabric springs 20 and 21, respectively, as shown in Fig. 1. The frame member 18 preferably has metal side bars 22 and 23 secured to one another by the underslung U-shaped bars

24 and 25. On the outer face of the wire fabric spring 20 there is secured the mattress section 26 which extends beyond the front edge of the frame member 18 a short distance, as shown in Fig. 3, and has hingedly connected to its front upper edge by a fabric hinge 27, the mattress section 28 which, see Fig. 3, is slightly narrower than the mattress section 26 so that when folded over upon the mattress section 26 in couch or love seat formation its rear end will be spaced from the rear end of the mattress section 26. The rear edge of the mattress section 26 also is provided with a fabric sheet or flap 111 in area approximating that of the main outer face of the upholstered portion 11 of the frame, or section 2, so that in bed formation, see Fig. 2, the flap 111 will effectively cover the decorative outer face of the upholstered portion 11.

30 The frames 3 and 4 in the embodiment shown function as complements of one another, in other words, in bed formation, that shown in Fig. 2, they are disposed in alignment with one another and their aligned position is dependent one upon the other, and, in turn, in chair or love seat formation, that shown in Fig. 4, their superimposed position is dependent one upon the other. This interdependence results from the linkage now to be described.

35 The frame 3 has pivotally connected to the outer faces of its side bars 22 and 23, adjacent its rear ends, one of the ends of the links 29 and 30, the other ends of which links 29 and 30 are pivotally connected to the inner faces of the side bars 5 and 6 a short distance from the rear ends of said side bars 5 and 6. To the outer faces of the intermediate portions of the side bars 22 and 23, in the present instance, slightly nearer to the front ends than to the rear ends of the side bars 22 and 23, there are pivotally connected the intermediate portions of the bent levers 31 and 32, one of the ends of said levers 31 and 32 being pivotally connected to the inner faces of the side bars 5 and 6 adjacent the front ends thereof, and the other ends of said levers 31 and 32 are connected to one of the ends of the bent levers 33 and 34, the other ends of which bent levers 33 and 34 are connected to the legs 35 and 36, respectively. The intermediate portions of the levers 33 and 34, nearer to the pivots 37 with the legs 35 and 36 than to the pivots 38 with the levers 31 and 32, are pivotally connected at 119 to the outer faces of the section 4.

40 To the inner faces of the front ends of the side bars 5 and 6 there are pivotally connected to one of the ends of the side bars 39 a foot-board or baseboard 40. The baseboard 40 extends to the rear of the front ends of the side bars 5 and 6 when in horizontal position, see Fig. 2, such front ends as at 41 being rounded so that the baseboard 40 clears the same with facility when moving from a vertical to a horizontal position and the front edges of the side bars 5 and 6 serve as limiting stops for the baseboard 40 in vertical position, see Fig. 4, and the lower edges of the side bars 5 and 6, see Fig. 2, serve as limiting stops for the baseboard 40. The inner faces of the side bars 39 at 42 of the baseboard 40 are, in turn, pivotally connected to one of the ends of the links 43 and 44, the other ends of the links 43 and 44 being pivotally connected to the levers 31 and 32 adjacent their pivots 45 with the side bars 5 and 6. The baseboard 40, from the foregoing, will be seen to determine the position of the section 3 either in its raised position, that shown in Fig. 2, or in its descended position, that

5 shown in Fig. 4, although in descended position, that shown in Fig. 4, section 3 rests in the side bars 5 and 6 of the main frame 1 and the sides 22 and 23 of the section 3 rest on the rubber bumpers 122 which are mounted on the angular braces 123 which serve as stiffener bars for the main frame 1.

10 The movable sections or frames 3 and 4 are also connected by a pair of links 46 and 47 which are connected to one another by the underslung U-shaped bracing bar 48. One of the ends of the links 46 and 47 are, in turn, pivotally connected to the inner faces of the side bars 22 and 23 of the frame 3 near the front ends of the frame 3, and the other ends of the links 46 and 47 are pivotally connected to the inner faces of the side bars 49 and 50 of the frame 4 by the pivots 51.

15 The legs 35 and 36 in order to close and open with the movement of the frame or section 4 are pivotally connected by the links 52 and 53 with the side bars 49 and 50, one of the ends of the links 52 and 53 being connected by the outer faces of the legs 35 and 36 a short distance removed from the pivot pins 37, and the other ends of the links 52 and 53 pivotally connected to the outer faces of the side bars 49 and 50 a short distance from the free ends thereof, see Fig. 2.

20 The links 46 and 47 are, in turn, connected to the levers 31 and 32 by the links 54 and 55, the link 54 being pivotally connected to the outer face of the link 46 and to the outer face of the lever 31 intermediate the pivot 38 and the pivotal connection of the lever 31 with the side bar 22, and the link 55 being pivotally connected to the outer face of the link 47 and to the outer face of the lever 32 intermediate the pivot 38 and pivotal connection of the lever 32 with the side bar 23.

25 In order to counteract the weight to dampen the sound when moving from one formation into another, the springs 56 and 57 are provided, the spring 56 being connected at one end to the link 46 and at its other end to the lever 31 intermediate the pivot 38 and the pivotal connection of the lever 31 and the link 54, and the spring 57 being connected at one end to the link 47 and at its other end to the lever 32 intermediate the pivot 38 and the pivotal connection of the lever 32 with the link 55.

30 From the foregoing it will be seen that the sections 3 and 4 can operate independent of the section 1 to form a two section bed or seat at one time and at another time to form a mattress compartment. In other words, in one formation, that shown in Fig. 2, the sections 3 and 4 will be in alignment with one another, the section 3 being in its raised position with the links 46 and 47 in substantial alignment with the sections 3 and 4. In such bed formation the legs 35 and 36 will be in vertical position, that shown in Fig. 2, and the bed section 4 in part supported thereon, and otherwise cooperating with the links 46 and 47 and section 3 to be supported by the linkage in connecting the bed sections 3 and 4 with one another and with the frame 1. In such horizontal position the mattress section 26 will be swung over from the mattress section 26 about the hinge 27 to rest on the frame 4. Preferably, the lower face of the mattress section 26 is secured to the upper face of the frame 3.

35 As shown in Fig. 2, preferably one face of the frame 4 is provided with an ornamental fabric covering 58. This fabric covering the face of the

frame 4 which faces downwardly in the position shown in Fig. 2 and upwardly in the love seat formation, that shown in Fig. 4. This fabric 58 particularly extends over the longitudinal end of the frame 4 adjacent the pivots 51 so that in love seat formation, it may cooperate with the covering on the baseboard 40 and on the cushion 59 to harmonize with the color scheme adopted for the love seat as a piece of furniture. In love seat formation, the mattress section 28 is folded over onto the mattress section 26 and then appears in the chamber formed between the frame 3 and the frame 4, see Fig. 4. After the frames 3 and 4 have been so positioned, the cushion or cushions 59 may be placed upon the section 4 to complete the love seat assembly.

In the interest of the comfort of the sleeper or person who lies prone on the mattress elements 27 and 28 of the sections 3 and 4 in bed formation, it will be noted that in the first place the baseboard 40 drops away from the sections 3 and 4 so that under no circumstances may or will the body of the occupant depress the spring fabric of the section 3 into engagement with the upper edge of the baseboard 40. In turn, it will be noted that the ends of the frames 3 and 4 adjacent one another in bed formation do not have transversely extending bars in alignment with the side bars 22, 23 of the section 3 and the side bars 49 and 50 of the section 4. However, to brace the adjacent ends of the frames 3 and 4 in such bed formation, the underslung U-shaped bars 24 and 25 are provided and connected to the side bars 22 and 23 of section 3, and the underslung U-shaped bar 48 of the links 46 and 47 provided to cooperate with the adjacent ends of the side bars 49 and 50 of section 4 and yet permit the body of the occupant amply to depress the spring fabric of the sections 3 and 4 to satisfy his comfort. The other end of the frame 4, as clearly shown in Fig. 1, has its side bars connected to one another by the tie bar 118.

When section 2 is used with sections 3 and 4 to form a back member in love seat formation, that shown in Fig. 4, and, in turn, a third bed section in bed formation, that shown in Fig. 2, preferably the links 13 and 14 are connected by the links 60 and 61, respectively, to the links 29 and 30, respectively. Links 60, 61 at one of their ends are pivotally connected to the inner faces of the links 13 and 14 near the lower ends of the links 13 and 14, and the other ends of the links 60 and 61 are pivotally connected to the outer faces of the links 29 and 30 near the lower ends of the links 29 and 30.

When so connected, see Figs. 2, 3 and 4, a bed formation is formed where the upholstered back portion 11 cooperates with the mattress sections 26 and 28 to form a substantially aligned upper level with the flap 111 of the mattress section 28 extending over the outer face of the upholstered portion 11, see Fig. 2. If it is now desired to convert this couch bed into a love seat or couch, the several parts will first pass through the position illustrated in Fig. 3. In other words, initially the flap 111 will be folded over onto the upper face of the mattress section 26, thereupon the mattress section 28 folded over onto the flap 111 and then the outer end of the section 4 raised when it will not only retract the legs 35 and 36 into the position shown in Fig. 4, but will also depress the frame 3 down to the level of the side bars 5 and 6, as shown in Fig. 4, but also swing upwardly the baseboard 40 into the final vertical position shown in Fig. 4 and also rock the links 13, 14, 15

and 16 rearwardly at the same time to raise the upholstered portion 11 into the inclined erect position shown in Fig. 4. Thereupon, the upholstered seat portion or portions 59 may be placed in position on the section 4.

The pivots 38 are provided with inward extensions 138, see particularly Fig. 6, to form limiting stops for receiving the edges of the side bars 49 and 50 in love seat formation, that shown in Fig. 4.

In order to eliminate undue movement of the respective parts when the sections are in love seat arrangement, there is formed on the links 52 and 53 the inwardly extending studs 62 and 63, respectively. These studs in love seat arrangement, see particularly Fig. 4, will engage the legs 35 and 36, in turn, to press such legs against portions of the levers 33 and 34 and such portions of the levers 33 and 34 against the outer faces of the side bars 49 and 50 in wedging relation with one another.

It is obvious that various changes and modifications may be made to the details of construction without departing from the general spirit and scope of the invention as set forth in the appended claims.

I claim:

1. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section; a second pair of levers operatively connecting said second bed section to said legs and to said first pair of levers, and a third pair of links operatively associating said fixed frame with said first bed section and parallel to a pair of one of the arms of said first pair of levers.

2. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section and parallel to a pair of one of the arms of said first pair of levers, and a fourth pair of links operatively connecting said first pair of links to said first pair of levers.

3. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section and parallel to a pair of one of the arms of said first pair of levers, a fourth pair of links operatively connecting said first pair of links to

said first pair of levers, and springs operatively connecting said second pair of links to said first pair of levers.

4. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section parallel to a pair of one of the arms of said first pair of levers, a baseboard pivotally connected to said fixed frame, and a fourth pair of links operatively connecting said baseboard to said first pair of levers.

5. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section parallel to a pair of one of the arms of said first pair of levers, a first mattress section secured to the upper face of said first bed section, a second mattress section pivotally connected to said first mattress section and movable either to be superimposed upon said first mattress section when said first bed section is depressed or to be swung over and rest on said second bed section when said second bed section is disposed in alignment with said first bed section that is in bed formation.

6. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section and parallel to a pair of one of the arms of said first pair of levers, a baseboard pivotally connected at one end to said fixed frame, a fourth pair of links pivotally connected to the other end of said baseboard and to said first pair of levers, and a portion of said baseboard engaging said fixed frame to form a limiting stop when actuated into a depressed or horizontal position and also to form a limiting stop when actuated into a raised or vertical position.

7. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section parallel to a pair of one of the arms of said first pair of levers, a first mattress section secured to the upper face of said first bed section, and a second

a pair of one of the arms of said first pair of levers, said fixed frame having a pair of horizontally extending side bars having vertically extending abutting faces and lower horizontally extending abutting faces and intervening rounded portions, a baseboard pivotally connected adjacent one of its ends and adjacent said abutting faces with a part of said baseboard engaging said vertically extending abutting faces as limiting stops when actuated into a raised or vertical position and engaging said horizontally extending abutting faces as limiting stops when actuated into a depressed or horizontal position.

8. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section parallel to a pair of one of the arms of said first pair of levers, a first mattress section secured to the upper face of said first bed section, a second mattress section pivotally connected to said first mattress section and movable either to be superimposed upon said first mattress section when said first bed section is depressed or to be swung over and rest on said second bed section when said second bed section is disposed in alignment with said first bed section that is in bed formation.

9. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, and a third pair of links operatively associating said fixed frame with said first bed section and parallel to a pair of one of the arms of said first pair of levers, said first bed section being lowered when said second bed section is swung over into seat formation to form a mattress compartment between said two bed sections.

10. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section and parallel to a pair of one of the arms of said first pair of levers, said first bed section being lowered when said second bed section is swung over into seat formation to form a mattress compartment between said two bed sections, a first mattress section secured to the upper face of said first bed section, and a second

mattress section pivotally connected to said first mattress section and movable either to be superimposed upon said first mattress section when said first bed section is depressed or to be swung over and rest on said second bed section when said second bed section is disposed in alignment with said first bed section that is in bed formation.

11. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section and parallel to a pair of one of the arms of said first pair of levers, an interchangeable back and bed section, two pairs of links pivotally connecting said interchangeable section to said fixed frame, and a fourth pair of links operatively associating said third pair of links with one of the pairs of said latter two pairs of links.

12. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section parallel to a pair of one of the arms of said first pair of levers, an interchangeable back and bed section, two pairs of links pivotally connecting said interchangeable section to said fixed frame, a fourth pair of links operatively associating said third pair of links with one of the pairs of said latter two pairs of links, and springs operatively connecting a pair of said two pairs of links with said fixed frame.

13. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section parallel to a pair of one of the arms of said first pair of levers, an interchangeable back and bed section, two pairs of links pivotally connecting said interchangeable section to said fixed frame, and a fourth pair of links operatively associating said third pair of links with one of the pairs of said latter two pairs of links, said fixed frame having a supporting frame portion to receive and aid in supporting said interchangeable section in bed formation.

14. The combination of a fixed frame, a first bed section, a pair of levers operatively associ-

ating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section parallel to a pair of one of the arms of said first pair of levers, an interchangeable back and bed section, two pairs of links pivotally connecting said interchangeable section to said fixed frame, a fourth pair of links operatively associating said third pair of links with one of the pairs of said latter two pairs of links, said fixed frame having a supporting frame portion to receive and aid in supporting said interchangeable section in bed formation, and springs operatively connecting a pair of said two pairs of links with said supporting frame portion.

15. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, and a third pair of links operatively associating said fixed frame with said first bed section parallel to a pair of one of the arms of said first pair of levers, the pivotal connection of said first pair of levers and said second pair of levers including extensions to engage and aid in supporting said second bed section in seat formation.

16. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section parallel to a pair of one of the arms of said first pair of levers, and extensions on said second pair of links engaging said legs in turn to press parts of said second levers against the sides of said second bed section in seat formation to prevent undue movement of the operating parts in seat formation.

17. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section parallel

to a pair of one of the arms of said first pair of levers, an interchangeable back and bed section, two pairs of links pivotally connecting said interchangeable section to said fixed frame, a fourth pair of links operatively associating said third pair of links with one of the pairs of said latter two pairs of links, a first mattress section secured to the upper face of said first bed section, a second mattress section pivotally connected to said first mattress section and movable either to be superimposed upon said first mattress section when said first bed section is depressed or to be swung over and rest on said second bed section when said second bed section is disposed in alignment with said first bed section that is in bed formation.

18. The combination of a fixed frame, a first bed section, a pair of levers operatively associating said first bed section to said frame to control the elevation of said first bed section, a second bed section, a first pair of links operatively connecting said second bed section to said first bed section, legs for said second bed section, a second pair of links operatively connecting said legs to said second bed section, a second pair of levers operatively connecting said second bed section to said legs and to said first pair of levers, a third pair of links operatively associating said fixed frame with said first bed section parallel to a pair of one of the arms of said first pair of levers, an interchangeable back and bed section, two pairs of links pivotally connecting said interchangeable section to said fixed frame, a fourth pair of links operatively associating said third pair of links with one of the pairs of said latter two pairs of links, a first mattress section secured to the upper face of said first bed section, a second mattress section pivotally connected to said first mattress section and movable either to be superimposed upon said first mattress section when said first bed section is depressed or to be swung over and rest on said second bed

section when said second bed section is disposed in alignment with said first bed section that is in bed formation, and a flap connected to said first mattress section and movable to be stretched across said interchangeable section in bed formation.

19. The combination of a fixed frame, a first bed section, a pair of levers operatively associating said first bed section to said frame to control the elevation of said first bed section, a second bed section, means for operatively connecting said second bed section to said first bed section, legs for said second bed section, a first pair of links operatively connecting said legs to said second bed section, a second pair of levers operatively connecting said second bed section to said legs, and to said first pair of levers, and a second pair of links operatively associating said fixed frame with said first bed section and parallel to a pair of one of the arms of said first pair of levers.

20. A combination of a fixed frame, a first bed section, a pair of levers operatively associating said first bed section to said frame to control the elevation of said first bed section, a second bed section, means for operatively connecting said second bed section to said first bed section, legs for said second bed section, a first pair of links operatively connecting said legs to said second bed section, a second pair of levers operatively connecting said second bed section to said legs and to said first pair of levers, a second pair of links operatively associating said fixed frame with said first bed section and parallel to a pair of one of the arms of said first pair of levers, an interchangeable back and bed section, two pairs of links pivotally connecting said interchangeable section to said fixed frame, and a third pair of links operatively associating said second pair of links with one of the pairs of said latter two pairs of links.

JOSEPH MARTIN.
